William Phelan

UNITED STATES PATENT OFFICE.

WILLIAM PHELAN, OF PEORIA, ILLINOIS.

IMPROVEMENT IN STEAM-GENERATORS.

Specification forming part of Letters Patent No. 56,796, dated July 31, 1866.

To all whom it may concern:

Be it known that I, WILLIAM PHELAN, of the city and county of Peoria, and State of Illinois, have made new and useful Improvements in Steam-Boilers; and I do hereby declare the following to be a full, clear, and exact description of the nature, construction, and operation of the same, sufficient to enable one skilled in the art to which it appertains to construct and use the same, reference being had to the accompanying drawings, which are made part of this specification, in which—

Figure 1 is a perspective view of the boiler. Fig. 2 is a perspective view of the removable arrangement of fire-box, double set of flues, and flue-chamber. Fig. 3 is a vertical central longitudinal section. Fig. 4 is a front end elevation with the furnace doors removed. Fig. 5 is a vertical transverse section on line A A, Fig. 3. Fig. 6 is a top view of the front end of the return-flues above the fire-box. Fig. 7 is a vertical transverse section on the line B B, Fig. 3. Fig. 8 is a vertical transverse section on the line C C, Fig. 3.

The boiler consists of an outer shell and an interior arrangement of fire-box, reverberating-flues, and rear flue-chamber, which are so attached together and secured in the said shell as to be removable therefrom, the space around the said fire-box, flues, and chamber inclosed by the said shell forming a water and steam jacket when the parts are in position and in operation.

The depressions in the sides of the boiler at the lines of junction of the cylindrical fire-box and the shell around the flues are covered in by plates which form steam-chambers A B.

In the drawings, A is the steam-drum on the left, and B the steam-drum on the right, of the boiler. Into these drums the steam is conducted by a pipe from the top of the boiler.

C indicates the front smoke-stack doors, one of which is open in Fig. 4, showing the front end of some of the return-flues and affording the means of getting at said flues for cleaning.

D shows a movable hinge-pin, which may be taken out when the movable fire-box, flues, &c., are required to be removed from the shell.

F is the flange on the front end of the shell, to which is bolted the flange F on the front end of the movable fire-box, &c.; G, the door of the fire-box, shown as open in Fig. 4, affording the means of feeding the fire and cleansing the lower set of flues; H, the draft-opening for the admission of air under the grate-bars; I, water-space around the fire-box, flues, and rear flue-chamber; J K, the hand-holes for cleansing the water-space below the fire-box. L, Fig. 3, is the flue-sheet at the back of the fire-box. M is the fire-box; N, the front end, the rear flue-chamber, O, receiving both sets of flues; P, the back end of the shell; O, the opening at the lower side of flue-chamber, passing across the intervening space and through the shell; V, the cover of the same. R is a stay-bolt on the rear end of the boiler. T is the stack, so bolted to the jacket as to be detachable therefrom when the interior portion (consisting of the fire-box, double set of flues, and flue-chamber O) is to be removed; V, supplementary fire-doors for regulating draft of air to the furnace.

The volatile results of combustion pass from the fire-box through the lower set of flues into the chamber O, and thence return through the upper set of flues to the stack.

Having described my invention, what I claim therein as new, and desire to secure by Letters Patent, is—

1. In combination with an outer shell or jacket, the removable arrangement of fire-box, double set of flues, and flue-chamber O, so attached to the outer shell as to permit the space between them to be used as a water and steam chamber, I.

2. In combination with the said shell surrounding the said removable arrangement, steam-chambers A B on the sides of the boiler, substantially as described.

WILLIAM PHELAN.
